UNITED STATES PATENT OFFICE

2,513,582

MATTRESS HANDLE

Martin L. Nattenheimer, Chicago, Ill.

Application December 20, 1945, Serial No. 636,084

1 Claim. (Cl. 5—345)

1

This invention relates to mattress handles and aims to provide a mattress handle which will be simple, economical to make, and which will be rugged and have a long useful life. A simple embodiment of the invention is disclosed in connection with the drawings, it being understood, however, that various modifications of the structure may be made without departing from the spirit of the invention.

Referring to the drawings, Figure 1 shows an elevation of a portion of a mattress provided with a handle embodying the present invention. Figure 2 is a sectional detail on line 2—2 of Figure 1.

The mattress with which the improved handle may be used may be of any type whatsoever. As illustrated here, the mattress is the so-called inner spring variety having coil springs 10, of which only one is shown, extending between metal frame members 11 and 12. Suitable padding 15 may be provided, and the entire mattress covered with outer fabric material 16.

In accordance with customary procedure, seams 18 and 19 at the top and bottom may be provided around the edge of the mattress. Such seams are usually bound and stitched in a well-known manner.

In accordance with the invention, side 20 of the mattress between seams 18 and 19 has at spaced points 21 and 22 eyelets 23 of brass or any other suitable material. Such eyelets have perforated cupped walls 24 through which air may pass from the outside to the inside of the mattress. Supported by a pair of eyelets is handle 26 of any suitable rigid material such as wood, metal, or some plastic. Handle 26 is provided with suitable apertures through which the eyelets may be threaded before being spread in position.

In order to re-enforce the entire structure, each eyelet has textile strip 28 rigidly fastened thereto. Thus, strip 28 may be of heavy canvas or any other fabric and extends toward seams 18 and 19 respectively. Strips 28 extend far enough so that the ends thereof are stitched to the mattress proper at seams 18 and 19.

2

In practice, eyelet 23 will be threaded through the registering openings of handle 26, mattress side 20 and textile strip 28. The eyelet may then be bent back in the usual fashion to rigidly anchor the same in position. The ends of strip 28 may be sewed in seams 18 and 19 in course of manufacture.

It will be evident that any strains on handle 26 will be distributed over a substantial portion 10 of the mattress. Thus, textile strips 28 will transfer the load to heavy seams 18 and 19 and reduce the strain on the eyelet anchorage.

If desired, textile strips 28 may be disposed on the outside of the mattress. It is preferred, 15 however, to dispose these strips on the inside for obvious reasons. Each mattress may have as many handles as necessary.

What is claimed is:

In a mattress having top, bottom and sides 20 with edge seams at the junction of a side and top or a side and bottom, a handle structure comprising a handle of rigid material disposed at the side, an eyelet at each end of said handle passing through an aperture in said handle, 25 said eyelet joining said handle and mattress side, and a textile strip for each eyelet, said textile strip being rigidly anchored to its eyelet and extending to the seams at the top and bottom of said mattress and being sewed at the edge seams.

MARTIN L. NATTENHEIMER.
